UNITED STATES PATENT OFFICE.

HERBERT AUSTIN, OF BROMSGROVE, ENGLAND.

MANUFACTURE OF EXPLOSIVE SHELLS.

1,191,490.

Specification of Letters Patent. Patented July 18, 1916.

Application filed March 7, 1916. Serial No. 82,730.

To all whom it may concern:

Be it known that I, HERBERT AUSTIN, a subject of the King of Great Britain, and residing at Bromsgrove, in the county of

5 Worcester, England, engineer, have invented certain new and useful Improvements in the Manufacture of Explosive Shells, of which the following is a specification.

10 In the manufacture of an explosive shell there is a liability, if the base of the shell is entirely integral with the main structure, of such porosity or piping in the base as will cause the explosion of the ammunition, 15 by which the shell is fired from a gun, to fire the explosive charge within the shell; and to avoid this it has been a practice to turn out a considerable portion of the thickness of the metal of the base and to screw 20 a plate therein, and then to rivet the back edge of the plate into a slight rabbet or recess which surrounds the outer edge of the screwed opening, or the edge of the opening which might be riveted into a slight rabbet or 25 recess left by suitably shaping the back corner of the plate. The riveting, however, tends to unscrew and loosen the plate somewhat within the opening within which it has been screwed; and the main object of 30 this invention is to avoid any risk that the process of riveting will unscrew in any degree and loosen the plate.

According to this invention, after the plate has been tightly screwed up within the 35 base of the shell, it is submitted, during the time that the riveting of the edge thereof, or of the opening into which it has been screwed, is effected, to a twisting strain, that is to say, a strain which tends to turn 40 the plate in relation to the shell, exerted in the direction in which the plate has been screwed up. The twisting strain upon the plate, exerted in the direction in which the plate has been previously tightly screwed up, 45 prevents any turning back of the plate, in relation to the shell, under the riveting operation, and the plate consequently remains tightly screwed up throughout such operation. The particular means which may be 50 employed for the purpose of the invention may vary considerably. According to the most elementary form thereof, the plug might be held tightly screwed up by hand, such as through the medium of the spanner 55 by which it has been screwed up, and the riveting might be performed by means of

a hand hammer. I have, however, devised apparatus which is particularly convenient for the purpose, and this I will proceed to describe by reference to the drawings, here- 60 with:

Of these drawings:—Figure 1 illustrates a front view of the apparatus. Fig. 2 is a side elevation, partly in section, of the apparatus shown by Fig. 1; and, Fig. 3 is a de- 65 tached plan view of a detail of the apparatus.

A is the machine bed and B a pillar which stands up therefrom.

C (shown by broken lines Fig. 2) is a 70 vertical pillar which is capable of revolving within the bed A and carries at its upper end a quick-action chuck D.

A shell E, which is to be operated upon by the machine, is shown by broken lines 75 (Fig. 1) to be held in an inverted position by the chuck D, and during the riveting operation the shell is revolved by revolving the pillar C. The plate which is to be riveted in place in the base of the shell is 80 screwed tightly up within the base prior to gripping the shell within the chuck D.

f is the operative portion of a tool through the medium of which the strain tending to maintain the plate tightly screwed up is put 85 upon the plate. This portion f of the tool is carried by a spindle F which is revoluble within a holder G, but any turning movement of the spindle F in relation to the holder is checked by means of a friction 90 clutch H, such as of the plate type, as shown. The holder G is slideable vertically along guides of the pillar B. When the shell has been secured within the chuck D the holder G is brought down to engage the operative 95 portion of the tool f with the plate of the shell in a manner to insure that the plate cannot turn without turning the tool.

K K are a pair of pneumatic riveters which are carried at opposite sides of the 100 holder G by means of a ring G¹ which is fixed around the lower end of the holder, being conveniently clamped to such ring by the clamps k.

The operation of the machine is as fol- 105 lows:—As the pillar C, and consequently the shell E, revolves, the operative portion f of the tool and the spindle F revolve there- with, but the friction clutch H offers such considerable resistance to the turning of the 110 spindle F as to insure that there will be a constant strain upon the plate of the shell

which tends to prevent it turning with the shell, and this strain is exerted in the direction in which the plate has been screwed up within the base of the shell. During the 5 revolution of the shell, the pneumatic riveters perform their operation and the twisting strain which is put upon the plate during its revolution prevents the plate from unscrewing in any degree within the base of the 10 shell while the riveting is being performed. The pillar C conveniently revolves within a vertical cylindrical casing L of the bed A, and is conveniently driven through the medium of a worm M of a shaft M¹ and a 15 worm wheel N which is formed with or fixed around the lower portion of the pillar C. The shaft M¹ is shown to be driven by a belt m from a pulley P, of a shaft P¹, which transmits motion to a pulley Q of the shaft 20 M¹. The pulley P is of a width to allow the belt to be moved from the pulley Q on to a loose pulley Q¹ when the revolution of the pillar C is to stop. The belt is conveniently shifted by means of a pedal R operating 25 through a rock shaft r and belt-shifter r'. The shaft P¹ is driven in any suitable manner from the source of power.

The tool holder G is formed in two main parts, namely, the part which directly carries the spindle F and a part G² in relation 30 to which it is adjustable sidewise along guides thereof and is fixed in the position required by set-screws g. The part G² is 35 slidable vertically along guides b of the pillar B, and the weight of the tool holder and tool is balanced, or largely so, by a balance-weight S which depends from one end of a flexible connector s which passes 40 from the weight over a pulley T and thence down to its connection with the part G² of the holder. Within a housing g' of the part G² is located a toothed wheel g² which gears 45 with a vertical rack B¹ which is fixed within the pillar B. On one end of the spindle of the toothed wheel g² is fixed a capstan wheel g³ by which the wheel g² may be turned to bring the tool holder down to suitably engage the tool with the plate of the shell. The tool may be held down by means of 50 the capstan wheel while the riveting operation is performed.

Conveniently, the operative portion f of the tool is formed similarly to the operative

end of a screw-driver, to engage with a saw-cut of a projection from the middle of the 55 back of the plate.

The plate clutch H is of a well-known type in which alternate plates of a series which are pressed together by springs engage at their outer edges with keys of the 60 casing within which they are contained, and the other plates engage at their inner edges with keys of a part which is capable of turning in relation to the case. Fig. 3 shows a ring which passes over the upper end of the 65 spindle F and has inward keys v to engage with keyways of the spindle and outward keys v' to engage with alternate plates of the clutch.

Having fully described my invention, 70 what I claim and desire to secure by Letters Patent, is:—

1. In the manufacture of an explosive shell in which a plate is screwed into a recess in the base thereof and is then further 75 secured by riveting, submitting the plate, after it has been tightly screwed up, during the time that the riveting is effected, to a twisting strain exerted in the direction in which the plate has been screwed up. 80

2. In the manufacture of an explosive shell in which a plate is screwed into a recess in the base thereof and is then further secured by riveting, submitting the plate, after it has been tightly screwed up, during 85 the time that the riveting is effected, to a twisting strain which is maintained by frictional resistance, substantially as set forth.

3. In an apparatus used in the manufacture of explosive shells, the combination of 90 means for riveting to the base of a shell a protective plate screwed therein and means for imparting during the riveting operation a torsional stress to said plate in the direction in which the plate is screwed up, said 95 stress being operative to prevent an unscrewing or loosening of the plate during such riveting operation.

In witness whereof I have hereunto signed 100 my name this 17th day of February, 1916, in the presence of two subscribing witnesses.

HERBERT AUSTIN.
